LOOSE LEAF BINDER

Filed Feb. 23, 1928

UNITED STATES PATENT OFFICE.

ADOLPH G. LOTTER, OF MILWAUKEE, WISCONSIN, ASSIGNOR, BY MESN~~E~~ ASSIGNMENTS, TO STATIONERS LOOSE LEAF COMPANY, OF MILWAUKEE, WISCONSIN, A CORPORATION OF WISCONSIN.

LOOSE-LEAF BINDER.

Application filed February 23, 1928. Serial No. 256,373.

This invention relates to certain new and useful improvements in loose leaf binders and refers more particularly to the binder head per se. In the conventional loose leaf binder, a pair of heads are connected by post members which pass through the leaves and are operable to accommodate various quantities of leaves. In the present embodiment, the post members are of the flexible type and 10 their free ends pass through apertures in one of the heads and are connected with screw means for retracting and extending the posts, and this invention has as one of its objects the provision of improved means for guiding 15 the posts through the apertures which means is formed of a single piece of bendable metal.

Another object of this invention resides in the provision of improved means for connecting the ends of the flexible binder posts with 20 adjusting screw means which obviates the usual rivet and reduces the cost of manufacture.

A further object of this invention resides in the provision of bearing members for the 25 adjusting screw means which are each formed of a single piece of bendable metal and act as reinforcing members between the channel shaped sections of the head to provide a rigid support and prevent crushing of the sections 30 during riveting of head sections.

And a still further object of this invention resides in the provision of a head member for a loose leaf binder, which has a minimum 35 number of parts so formed as to permit their production in quantities at a relatively low cost.

With the above and other objects in view which appear as the description proceeds, my invention resides in the novel construction, 40 combination and arrangement of parts substantially as hereinafter described and more particularly defined by the appended claims, it being understood that such changes in the precise embodiment of the herein disclosed 45 invention may be made as come within the scope of the claims.

In the accompanying drawing, I have illustrated one complete example of the physical embodiment of my invention constructed according to the best mode I have so far de-

vised for the practical application of the principles thereof, and in which:

Figure 1 is a side view of a pair of binder heads embodying my invention, parts thereof being broken away and in section to illustrate constructional details thereof; 55

Figure 2 is a view, taken through Figure 1 on the plane of the line 2—2;

Figure 3 is a transverse sectional view taken through Figure 1 on the plane of the 60 line 3—3;

Figure 4 is a detail, perspective view of one of the bearing members;

Figure 5 is a transverse, sectional view taken through Figure 1 on the plane of the 65 line 5—5; and

Figure 6 is a detail, perspective view of one of the guide members before its assembly with the head member.

Referring now more particularly to the 70 accompanying drawing, in which like numerals designate like parts throughout the several views, 5 and 6 designate the upper and lower heads of a loose leaf binder between which leaves, not shown, may be clamped. 75 Each head member is formed of a pair of channel shaped sections 7 arranged with the edges of their flanges abutting to provide a recess or chamber therebetween, and the ends thereof have end members 8 secured 80 thereto, between which the covers of the book (not shown) are hingedly mounted on rods 9.

The head members are adjustably connected by flexible binder posts 10 having their lower ends releasably secured in apertures 11 85 in the head member 6 by screw means 12 and their upper ends passed through apertures formed in the web of the inner channel section of the upper head member 5 to be connected with an adjusting screw 13, as will be 90 later described. The apertures in the head member 5 through which the flexible posts extend, are provided with guide members 14 which are substantially cup-shaped and each have a lug 15 extended rearwardly thereof to 95 engage the adjacent outer face of the head member and a pair of ears 16 adapted to be passed through openings 17 in the head member wall and struck over, as at 18, to maintain the guide member in position. That portion 100

of the head member wall just inwardly of each opening 17 is pressed upwardly, as at 19, to provide a rounded portion 20 over which the adjacent flexible post rides in its 5 movement in and out of the head interior.

The adjusting screw 13 is rotatably mounted at each end in bearing members 21 which also function as reinforcing members to prevent collapsing of the sections 7 during the insertion of rivets 22 which pass through aligned apertures in the members 7, 10 extended lugs 23 of the end member 8 and the bearing members 21, to rigidly connect the parts. Each bearing member is formed from a single piece of bendable metal and has its 15 ends folded upon themselves to provide a loop 24 in which the adjacent end of the screw is positioned and the upper end portion 25 thereof has upwardly extended side flanges 26 which extend to a height equal to the distance between the lugs 23 to provide the reinforcing means.

The adjusting screw has a right and left thread, each extending from the center to a 25 point adjacent the bearing members, and have nut members 27 threaded thereon. The members 27 are of a shape to conform with the interior of the head member 5 and are provided with recesses 28 in longitudinal alignment 30 with the apertures through which the flexible post members extend, to receive the adjacent ends 29 of the post members, drilled apertures 30 extending transversely with respect to the recesses 28 align with apertures in 35 the ends 29 and receive connecting pivot pins 31. The pins 31 are substantially loose in the drilled apertures and have their heads 32 positioned within counterbores 33 in the members 27 so that they are substantially flush 40 with the adjacent portions of the nut members, and as the members have a snug but sliding fit within the interior of the head, outward movement of the pins is prevented by the head side walls.

45 Rotation of the adjusting screw by means of the crank or key 33 moves the nut members towards and away from each other to either draw the flexible binder posts into the upper head and consequently move the heads together, or vice versa.

50 From the foregoing description, taken in connection with the accompanying drawing, it will be readily apparent to those skilled in the art to which an invention of this character appertains, that I have provided a loose leaf binder which is so constructed as to permit its production at a considerably reduced cost and in which the number of parts is reduced to a minimum.

60 What I claim as my invention is:

1. In a loose leaf binder, a binder head formed of channel members arranged with the edges of their flanges abutting to provide a chamber therebetween, end members having projections extending between the chan-

nel members at their ends, a substantially flexible post member having one end portion extensibly passed into the chamber of the binder head, screw means connected with said end portion to adjust the length of the post member 70 extended from the binder head, bearing members for the screw means formed of a single piece of bendable metal and providing a reinforcing member positioned between the projections of the end members to maintain the same in spaced relation, and securing means passed through aligned apertures in the channel members, the projections of the end members and the bearing members. 75

2. In a loose leaf binder including a binder head, a substantially flexible post member extensibly connected with the head and screw means connected with the post member to adjust its length extended from the head, bearing members for the screw means and located at each end of the binder head and formed from bendable metal by having their ends folded upon themselves to form loops in which the screw means is rotatably mounted, projections extended from one end of each bearing member at right angles thereto to provide reinforcing means between the walls of the binder head, and securing means passed through the walls of the binder head and the ends of the bearing members, the reinforcing means preventing the collapse of the binder head walls during insertion of the securing means. 90

3. In a loose leaf binder including a hollow binder head and a flexible post member adapted to be passed through an aperture in the wall of the head to extensibly lie therewithin, a substantially cup-shaped guide member positioned within the head and over the aperture, a lug carried by the guide member and passed through the aperture and engaging the outer face of the head, a pair of ears carried by the guide member and passed through adjacent apertures, said ears being struck over the head and, with the lug, securing the guide member in place, and a rounded portion over which the post member passed in its movement into and out of the head interior, said rounded portion being formed by striking a portion of the head wall 105 inwardly. 110

4. In a loose leaf binder including a hollow binder head, a flexible post member adapted to be passed through an aperture in one wall of the head to extensibly lie therein, an adjusting screw within the head and a nut member threaded on the screw, the nut member having a relatively snug fit within the head interior and having a transverse bore, and a pin loosely mounted in the nut member bore 120 for connecting the adjacent end of the flexible post member with the nut member, one side wall of the head member retaining the pin in position. 125

5. In a loose leaf binder including a hollow 130

binder head, a flexible post member adapted to be passed through an aperture in one wall of the head to extensibly lie therein, an adjusting screw within the head and a nut member threaded on the screw, the nut member having a relatively snug fit within the head interior and having a transverse bore counterbored at one end, and a headed pin loosely mounted in the nut member bore with its head 5 received in the counter-bore for connecting the adjacent end of the flexible post member with the nut member, one side wall of the head member closing the counter-bore to retain the pin in position.

10 15 In testimony whereof I hereunto affix my signature.

ADOLPH G. LOTTER.
